UNITED STATES PATENT OFFICE.

JACOB BROCKLEY, OF HAMPTON, VIRGINIA.

ARTICLE CARRIER AND DISPLAY DEVICE.

Application filed November 14, 1923. Serial No. 674,712.

To all whom it may concern:

Be it known that I, JACOB BROCKLEY, citizen of the United States, residing at Hampton, in the county of Elizabeth City 5 and State of Virginia, have invented certain new and useful Improvements in Article Carriers and Display Devices, of which the following is a specification.

This invention relates to an improved article carrier and display device of the general character disclosed in my pending application for a similar invention filed October 18, 1922, Serial No. 595,330, and seeks to provide a device of this character capable of carrying a half dozen or more articles while, at the same time, the structural parts of the device will be reduced to a minimum to thus facilitate manufacture while reducing the cost to the user.

Other and incidental objects will appear hereinafter.

In the drawings:

Figure 1 is a top plan view of my improved carrier,

Figure 2 is a side elevation of the device,

Figure 3 is an enlarged detail sectional view on the line 3—3 of Figure 1, looking in the direction of the arrows, and

Figure 4 is a bottom plan view of a 30 slightly modified construction.

In carrying the invention into effect, I employ an annular frame or ring 10 which is preferably stamped from suitable resilient sheet metal and extending diametrically of the ring are crossed brace bars 11. Connected at its lower end to the cross bars 11 at their point of intersection is a handle 12 terminating at its upper end in a finger loop 13, and mounted upon the ring is a plurality of article holders, the device shown embodying six of said holders. As brought out in detail in Figure 3 of the drawings, each of these holders comprises a pair of crossed substantially semi-circular spring clamps 14 deflected at their upper ends, as indicated at 15, to facilitate the insertion of an article therebetween, and mounting the clamps are legs 16, the several legs of the device depending beneath the ring 10 for supporting the carrier upon a table or other surface. Each of these legs is provided at its upper end with a reduced stud 17 defining a shoulder 18 and, as will be observed, the stud is inserted through the ring 10 and through a pair of clamps at their point of intersection so that the

shoulder 18 thus abuts the lower face of the ring while at its upper end, the stud is upset, as indicated at 19, for binding the clamps together. As exemplified in Figure 60 3, four of the legs 16 are disposed at the ends of the cross bars 11 so that the studs of said legs extend through the extremities of said bars for also connecting the bars with the ring 10. Thus, the legs not only 65 serve as supporting elements but also serve as fastening devices for the clamps and cross bars and, in this connection, it should be noted that the device is well adapted for use in cooking operations in any instance where it would be desired to space the articles being cooked from the bottom of a cooking vessel. As will be perceived, the cross bars 11 not only serve to brace the ring 10 but also provide a convenient 70 means for mounting the handle 12 centrally of the ring while by employing a ring to support the holders of the device a number of holders are compactly accommodated upon a single part. 75

In Figure 4 of the drawings, I have illustrated a slight modification of the invention wherein I employ a stamped resilient sheet metal frame embodying concentric inner and outer rings 20 and 21 connected 80 with each other by intersecting diametric integral cross bars 22 which also serve to brace each of the rings. As in the prior embodiment of the invention, a handle 23 is connected to the cross bars at their point 85 of intersection and mounted upon each of the rings 20 and 21 is a number of article holders, indicated as a whole at 24. These article holders are identical with the article holders of the construction first described 90 and are mounted by legs 25 identical with the legs 16. Thus, in this modification, a carrier of considerably increased capacity 95 is provided as compared with the structure using but a single ring.

Having thus described the invention, what is claimed as new is:

1. In an article carrier, the combination of a flat metal ring, flat intersecting metal cross bars extending diametrically of the ring and reinforcing said ring, a suspension device secured to said cross bars at the intersection thereof and upstanding therefrom axially of the ring, pairs of coacting spring clamps mounted on the ring and providing article carriers, corresponding clamps of said pairs of clamps being dis-

posed radially with respect to said suspension device and opposite corresponding clamps of said pairs of clamps being arranged directly above and being disposed to lie substantially within the lines of the inner and outer edges of said ring, and combined feet and fastening elements extending through the ring and through said pairs of clamps securing the clamps in position on the ring, said ring forming a continuous uninterrupted connection between the several pairs of article carriers.

2. In an article carrier, the combination of a unitary metal frame comprising inner and outer concentric rings connected with each other by integrally formed intersecting metal cross bars integral with the rings, a suspension device secured to and rising from the cross bars at their point of intersection axially of the ring, circumferentially spaced pairs of spring clamps mounted on the inner ring, circumferentially spaced

pairs of spring clamps mounted on the outer ring in staggered relation to the pairs of clamps on the inner ring, said pairs of clamps forming article holders, one of the spring clamps of each pair on the inner and outer ring being disposed radially with respect to the suspension device and the other spring clamp of each pair being disposed directly above and arranged to lie substantially within the lines of the inner and outer edges of the adjacent ring, and combined feet and fastening devices extending through the rings and through said pairs of clamps securing the clamps in position on the rings, said rings forming a continuous uninterrupted connection between the several pairs of article carriers supported thereby.

In testimony whereof I affix my signature.

JACOB BROCKLEY. [L.S.]
